MANUFACTURE OF AROMATIC ALCOHOLS

Ludwig Valik and Irene Valik, New York, N. Y.

No Drawing. Application March 20, 1933
Serial No. 661,844

13 Claims. (Cl. 260—153)

This invention relates to improvements in the manufacture of higher alcohols, and more particularly to such aromatic alcohols as the phenylethylalcohols, the tolylethylalcohols, the xylethylalcohols, the phenyl propylalcohols, the tolylpropylalcohols, the xylolpropylalcohols, hydratropic alcohols, methylbenzyl carbinol and homologues thereof. This application is a continuation in part of our application Ser. No. 10 614,840, filed June 1, 1932.

An object of this invention is to produce alcohols such as above referred to by reacting on aromatic hydrocarbons such as benzene, toluene, or xylene with an oxide such as ethylenoxide or 15 the various propylenoxides in the presence of an acid condensing agent.

Another object of this invention is to so control the temperature ranges of operation that a maximum quantity of the alcohol will be produced.

Another object of the invention is to reduce the production of side products such as dibenzyl and chlorhydrins, which have heretofore been formed in objectionable quantity in reactions of 25 this type and which are difficult of removal from the alcohol, and if not removed, impair its odor.

With these and other objects in view, the invention consists in the disclosures to be herein-after set forth and claimed, with the understanding that the several necessary elements comprising our invention may be varied in proportions and arrangement, without departing from the spirit and scope of the appended claims.

It is well known that in accordance with the 35 Friedel-Crafts reaction, aliphatic halogen compounds, in the presence of an acid condensing agent such as anhydrous aluminum chloride, react with aromatic hydrocarbons to form condensation products as the result of the elimination 40 of a hydrogen halide. Thus, a mixture of benzene, aluminum chloride and methylchloride react to form toluene and hydrogen chloride. But as toluene reacts under the same conditions with methylchloride to form xylene, and the latter to form trimethylbenzene, it is evident that 45 under the hitherto known conditions of operation for Friedel-Crafts synthesis, a pure compound could not be obtained.

Furthermore, it is known that the Friedel-Crafts synthesis may be used for the preparation 50 of dibenzyl from benzene, aluminum chloride, ethylenoxide, and hydrochloric acid. However, this process, conducted under conditions known in the art, has not produced more than a negligible percentage of phenylethyl alcohol ($C_6H_5CH_2CH_2OH$) or similar aromatic alcohols.

We have determined, through experimental research, that the aromatic alcohol yield can be materially increased and the dibenzyl yield decreased to substantially 1% of the total reaction

mass, i. e., the previously obtained by-product alcohol can be shifted to the main product, and the dibenzyl formerly obtained as the main product to a by-product, if proper conditions attend the reaction.

We have discovered that the excessive formation of dibenzyl, chlorhydrins, etc., can be prevented if the reaction with the liquid benzene and the condensing agent is conducted with a preferably gaseous alkylene oxide such as ethyleneoxide, propylene oxide, etc., (that is, at a temperature above the boiling point of 15° for ethylene oxide, and above 35° C. for propylene oxide) mixed with gas inert to the reaction, such as air. By this process using inert gas, the

side reactions of the alcohol and the benzene to form dibenzyl, and of the ethylene oxide and nascent HCl to form chlorhydrins are largely inhibited. The inert gas facilitates heat control, and also by reducing the nascent HCl concentration, reduces its detrimental effects. Thus, the yield of alcohol of higher initial purity than has heretofore been obtained is increased by one-half or more, without dilution of the reacting liquid by liquid solvents or diluents. While we prefer to use a temperature at which the alkylene oxide is gaseous, we do not so restrict ourselves, as we obtain increased yields and less side reactions at from —20° C. up, by using inert gas.

We have further discovered that a further increase up to 10% in the yield can be had by control of the exothermic reaction temperature through the use of lumps of aluminum chloride or other acid condensing agent (from about the size of a hazel nut to a large walnut) instead of powder or granulated size as heretofore proposed.

If the evolved HCl gas is neutralized as formed, as by addition of aliphatic or aromatic amines, ammonia, or other neutralizer, the yield is further increased.

Summarizing, we have first made a substantial gain over the prior art by using inert gas, and can increase this gain up to 10% by using lump condensing agent, and further increase the yield by using a neutralizer.

Example 1

In a suitable container in which there has been placed 500 grams of lump anhydrous $AlCl_3$, there is added 800 grams of benzene under stirring, 180 grams ethyleneoxide in gaseous form and an equal amount of air are passed through the mixture at 45°—55° C. until only a small amount of $AlCl_3$ has been left. The reaction container is constantly externally cooled with circulating water to maintain the desired temperature. The temperature is kept preferably within the range of about substantially 45° C.

to about substantially 55° C. but as hereafter seen can range from -20° C. upwards. The reaction product obtained is treated in the usual way with ice, separated and vacuum distilled. 5 In this reaction about 173 grams phenylethyl-alcohol and only 2 grams dibenzyl were formed.

Example 2

To 800 grams of toluene are added 500 grams 10 of lump anhydrous AlCl₃ through which is passed 180 grams of ethyleneoxide, preferably mixed with an equal amount of air or other inert gas with the temperature maintained by cooling at between 45 and 55° C., until the aluminum chloride 15 was practically used up. This gave a yield of 200 grams tolyl ethyl alcohol with only 2 grams of ditolyl and a negligible amount of chlorhydrin.

26

Example 3

Benzene	AlCl ₃	Prop. oxide	Temp.	Alcohol	Air
2250	1250	453	40-55	542	1:1

Example 4

The reaction was carried out under conditions similar to those employed in Example 1 30 with the exception that during the reaction period, triethanolamine was introduced slowly into the reaction container for the purpose of preventing the formation of substantial quantities 35 of ethylenechlorhydrin. By means of this alteration, a substantial improvement in the aromatic alcohol yield was accomplished.

Similar conditions can be used for the preparation of other aromatic alcohols such as tolyl- 40 ethylalcohol from toluene and ethylene oxide, xylylethylalcohol from xylene and ethylene oxide, phenylpropylalcohol and isomers from benzene and propylene oxide, tolylpropylalcohol and isomers from toluene and propylene oxide, and 45 xylylpropylalcohol and isomers from xylene and propylene oxide.

For comparative purposes other runs have been made as follows, using granular aluminum chloride without a neutralizer:

50

Benzene	AlCl ₃	Etox.	Temp.	Alcohol	Dibenzyl.	Etox. and air, approx. ratio
55	2250	1350	453	40-55	430	5 1:1
	2250	1350	453	40-45	471	4 1:1
	2250	1350	453	6-15	434	4 1:1
	2250	1350	453	25-35	422	Trace 1:1
	2250	1350	453	45-55	437	5 1:1
60	2250	1350	453	40-55	96	325 -----
	2250	1350	453	40-55		
Toluene	2300	1350	453	40-55	495	Trace 1:1
	2300	1350	453	40-55	460	Trace 1:1

65

At temperatures as low as -20° C. where the aromatic hydrocarbon is solid or viscous, a solvent such as petroleum ether is used, and the process carried on with inert gas as above described, with equally good results.

By using the lump aluminum chloride as hereinbefore mentioned, the above yields on commercial scale are about 10% higher, and by using a neutralizing agent as previously mentioned, the above yields further increase.

In any case the inert gas can be fed in separately during the reaction.

While we have above stated particular materials, conditions, proportions, and temperatures which have given the results stated, we do not 80 restrict ourselves thereto except as required by the scope of the appended claims, as we consider that we have discovered a type reaction applicable to a wide variety of Friedel-Crafts reactions, and desire to claim same accordingly. 85 In using the lump condensing agent, or a neutralizer, we do not restrict our claims to such use in connection with an inert gaseous mixture, but prefer to use all three in combination, and do not exclude the use of liquid organic solvents 90 or diluents.

The invention claimed is:

1. A process for the manufacture of aromatic alcohols comprising reacting an aromatic hydrocarbon with a gaseous mixture of alkylene oxide and inert gas in the presence of an acid 95 condensing agent.

2. A process for the manufacture of aromatic alcohols comprising reacting an aromatic hydrocarbon with a gaseous mixture of an alkylene 100 oxide and an inert gas in the presence of an acid condensing agent and a neutralizing agent.

3. A process for the manufacture of aromatic alcohols comprising reacting an aromatic hydrocarbon with ethyleneoxide in the presence 105 of an acid condensing agent and neutralizing the formed hydrogenchloride in status nascens with an aliphatic amine.

4. A process for the manufacture of aromatic alcohols comprising reacting an aromatic hydrocarbon with propyleneoxide in the presence 110 of an acid condensing agent and neutralizing the formed hydroniumchloride in status nascens with an aliphatic amine.

5. A process for the manufacture of aromatic 115 alcohols comprising reacting an aromatic hydrocarbon with an alkylene oxide in the presence of an acid condensing agent and neutralizing the formed hydrogenchloride in status nascens with an aromatic amine.

6. A process for the manufacture of aromatic alcohols comprising reacting an aromatic hydrocarbon with an oxide of the ethylene series and an inert gas in the presence of an acid condensing agent at a temperature of from substantially -20° C. to substantially 125 55° C.

7. A process for the manufacture of aromatic alcohols comprising reacting an aromatic hydrocarbon with a gaseous mixture of an oxide of the ethylene series and an inert gas in the 130 presence of an acid condensing agent at a temperature of from substantially -20° C to substantially 55° C.

8. A process for the manufacture of aromatic alcohols comprising reacting an aromatic hydrocarbon with a gaseous mixture of an oxide of the ethylene series and an inert gas in the 135 presence of an acid condensing agent at a temperature of from substantially 40° C. to substantially 55° C.

9. A process for the manufacture of aromatic alcohols comprising reacting an aromatic hydrocarbon with a gaseous mixture of an oxide of the ethylene series and an inert gas in the 140 presence of an acid condensing agent at a temperature of from substantially -20° C. to substantially 55° C., and neutralizing the acid reaction product as formed.
